BODY OPERATED SWITCH APPARATUS FOR
TIMING X-RAY EXPOSURES

Frank Mercer Gulland, Syracuse, N. Y.

Application March 28, 1938, Serial No. 198,576

1 Claim. (Cl. 200—97)

This invention relates to body operated switch apparatus for synchronizing X-ray exposures and has for an object to provide a mercury switch adapted to be mechanically operated by pulse, respiratory or other movements of a body or object, in combination with a delayed action relay, for the general purpose of timing exposures of X-ray and other photographs of moving objects such as the heart, lungs, and so forth by making successive short exposures of the object each time it reaches the same point in its motion cycle, until the total exposure time has elapsed.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawings forming part of this specification,

Figure 1 is a plan view of apparatus constructed in accordance with the invention.

Figure 2 is a longitudinal sectional view of the delayed action relay with parts in elevation.

Figure 3 is a longitudinal sectional view of the pulse operated mercury switch.

Figure 4 is a side elevation of a mercury switch showing the same operated by respiratory movement of the chest.

Figure 5 is a longitudinal sectional view of a modified form of switch adapted to be operated by movements of the body.

Figure 6 is a longitudinal sectional view of another modified form of switch of the pressure type.

Referring now to the drawings in which like characters of reference designate similar parts in the various views, and especially referring to Figure 3, it will be seen that the pulse operated switch comprises a frame 10 having spaced legs 11 to which a wrist strap 12 is buckled for mounting the device upon the wrist 13 of the subject, directly over any pulse. The frame is provided with a transparent tube 14 partly filled with a mercury column 15. The bottom of the tube is enlarged and is closed by a diaphragm 16 which is responsive to the pulse to raise and lower the mercury column.

An adjusting nut 17 is threadedly engaged with a nipple 18 through which the tube is slidably engaged. A helical spring 19 is sleeved on the tube between the nut and the enlarged base of the tube.

Switch contacts 20 are disposed within the tube

above the mercury level and are mounted in a threaded tubular holder 21 which is threadedly engaged in an adjusting nut 22 having a reduced end 23 engaged in an opening in the frame 10. A leaf spring 24 secures the nut in the opening and permits of the nut being turned to feed the holder 21 toward or away from the mercury tube in order to adjust the position of the switch contacts with respect to the top of the mercury column.

The adjusting nut 17 is screwed down and compresses the spring 19 which depresses the mercury tube until the mercury is seen to rise and fall steadily under impulse of the deforming of the diaphragm 16 by the pulse. The adjusting nut 15 22 is then turned to feed the holder 21 downward until contact is made between the switch contacts 20 and the mercury column 15 at each rise of the mercury column.

The switch controls a primary circuit indicated by wires 25 in Figure 1 and energized by a battery 26. The circuit wires are connected to the input of a delayed action relay 27 shown best in Figure 2.

The delayed action relay is for the purpose of converting the individual electrical impulses in the primary circuit, which are of undetermined and perhaps irregular length, into impulses in the secondary circuit which are controllably short, absolutely uniform, timed by the beginning only 30 of the primary impulse, and adjustable to occur automatically at any desired time after the primary impulse begins, up to nearly one whole motion cycle of the object. It comprises a frame 28 having mounted thereon a solenoid 29 which is 35 energized by the primary circuit. A tubular iron core or plunger 30 is slidably mounted in the solenoid and is provided with a flange 31 at the top to limit its fall, as well as for a purpose later described.

A non-ferrous stem 32 is slidably mounted in the tubular plunger and is provided at its upper end with a secondary bridging circuit closer 33. The tube is provided at its lower end with a retarding piston 34 which slidably fits in the cylinder 35 having an outwardly flared open upper end 36. Retarding movement of the piston is controlled by the amount of opening of a valve 37 in an air pipe 38 which communicates at one end with the atmosphere and at the other end opens 50 through a port 39 into the cylinder.

The bridging circuit closer 33 is insulated from the stem and is adapted to bridge secondary switch contacts 41 which are mounted upon an insulating diaphragm 42 carried by one end of a 55

- helical spring 43. The purpose of the spring is to cushion shock of impact of the bridging contact 33 and also this spring supplies the initial impetus downward to the stem 32. The opposite 5 end of the spring is secured in a cup 44 having a tubular stem 45 which is free to slide on a fixed rod 46. This permits the spring to release bell crank levers 47, the purpose of which will presently appear.
- 10 When the plunger 30 is moved upwardly by energizing of the solenoid the flange 31 moves upwardly and comes to rest on top of leaf springs 48 which are carried by pivoted levers 49 controlled by springs 50 to overlap and engage the bell crank levers 47 through lips 51 as shown. This upward movement of the plunger actuates a spring 51' which is sleeved upon the stem 32 and the spring raises the bridging contact 33. As the stem 32 rises it pulls upward the piston 34 which 15 fits closely in the cylinder 35, creating a suction which will delay the speed at which the stem rises depending upon the amount of air allowed to enter the cylinder through the valve 37. The piston rises at an even, predetermined rate, until 20 it reaches the flared portion of the cylinder, where air rushes around the edges of the piston and wholly releases the assembly of the stem 32 so that it shoots up to quickly close the secondary circuit at the contacts 33 and 41.
- 25 There is a slight dwelling of the bridging contact 33 on the contacts 41 due to the cushioning action of the spring 43, and this will be short if the spring 43 is strong and will be longer if the spring is weak, thus timing the length of each X-ray exposure.
- 30 After the spring 43 is compressed it actuates the bell cranks 47, which move the levers 49 to withdraw the springs 48 from underneath the flange 31 and release the plunger 30 allowing it 35 to drop to initial position for the next cycle if the primary circuit is by this time open, or allowing it to be pulled down to the electrical center ready to drop and wait for the next cycle if the primary circuit is still closed.
- 40 As the piston 34 returns to the cylinder a valve 40 carried by the piston will open under action of the accumulated air pressure and thus allows a quick drop. Meanwhile the springs 50 return the levers 49, bell cranks 47, and tubular stem 45 to 45 initial position. Should the voltage or current to be handled by this relay be excessive for the action above described an ordinary relay indicated by broken lines at 52 in Figure 1 may be connected in the secondary circuit between it and the 50 X-ray tube.
- 50 When the mercury switch is to be used in connection with respiratory movements it may, as in Figure 4, be clamped by a clamp 53 to a supporting arm 54 of any preferred type. A lever 55 is 55 hinged to the arm as shown at 56. The free end of the rod is disposed on top of the chest or diaphragm. A spindle 57 is adjustably secured to

the rod by a conventional swivel clamp 58 so that a head 59 on the spindle will engage underneath the enlarged bottom of the mercury tube 14. The switch is then adjusted as previously described in connection with pulse movements. The point of 5 the reciprocatory cycle to be photographed may be selected roughly by adjustment of the mercury switch, and the delayed action relay may be used for fine adjustment.

In Figure 5 there is shown a modified form of 10 switch which may be substituted for the mercury switch. In this form of the invention the primary circuit switch contacts 60 are carried by a threaded holder 61 engaged through a nut 62 which is carried by the top of a casing 63. A movable circuit closing contact 64 is secured to an arm 65 which projects from a stem 66 which projects through the bottom of the casing. The stem is connected to a lever 68 which is pivoted at one end as shown at 69 to the bottom of the casing 20 and is adapted to bear against some movable part of the body as indicated at 70. The casing may be adjustably secured to a standard 71 of any desired type.

A still further modified form of the invention is 25 shown in Figure 6. This form of the invention is a conventional pressure gauge in which a Bourdon tube 72 is provided at the free end with a bridging contact 73 adapted to engage stationary switch contacts 74 of the primary circuit, these latter 30 contacts being mounted upon and insulated from the casing 75 of the device. This switch is an alternative for the mercury switch shown in Figure 3, and is connected to a pressure bag, which is applied and inflated as in a sphygmomanometer. 35

From the above description it is thought that the construction and operation of the invention will be fully understood without further explanation.

What is claimed is:

A delayed action relay comprising a solenoid operated hollow plunger, a stem slidably mounted in the plunger, a spring sleeved on the stem, heads on the plunger and stem engaged in opposite ends 45 of the spring whereby the spring will be compressed by relative movement of the plunger and the stem, means for releasably engaging the head on the plunger to hold the spring in compression, a dash pot retarding device connected to the stem 50 for retarding movement of the stem by said spring when the plunger is attracted by energizing of the solenoid, a pair of switch contacts, a spring disposed adjacent to said contacts and adapted to be compressed by the head of the stem to cause a 55 dwell of the head on the contacts in circuit closing position due to the cushioning effect of the last named spring, and means connected to the last named spring for releasing said plunger to permit return of the stem to neutral position 60 after each actuation.

FRANK MERCER GULLAND.
